UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,079,957.

Specification of Letters Patent.

Patented Dec. 2, 1913.

Application filed June 20, 1913. Serial No. 774,767.

To all whom it may concern:

Be it known that I, GEORGE A. SEIB, a citizen of the United States, and resident of Ilion, in the county of Herkimer and State of New York, have invented certain new and useful Improvements in Type-Writing Machines, of which the following is a specification.

My invention relates to typewriting machines and more particularly to means for preventing the type faces from being injured by collision between the bars at or near the printing point.

One object of my invention, generally stated, is to provide simple and efficient means of the character specified.

To the above and other ends which will hereinafter appear, my invention consists in the features of construction, arrangements of parts and combinations of devices set forth in the following description and particularly pointed out in the appended claims.

In the accompanying drawing, Figure 1 is a skeletonized side elevation partly in section of a sufficient number of parts of one form of typewriting machine showing my invention in its embodiment therein. Fig. 2 is an enlarged detail fragmentary sectional view of a type bar constructed in accordance with my invention. Fig. 3 is a like view of the same but showing a modified form of construction.

I have shown my invention, in the present instance, embodied in a machine for preparing or "writing" stencil sheets or cards such as is disclosed in the application of A. W. Smith, Serial No. 752,848, filed March 8, 1913. It should be understood, however, that the invention may be embodied in various styles of typewriting machines whether or not such machines be equipped with needle faced types, although the invention was devised more especially for use in machines which employ needle faced types.

The invention is shown in the present case embodied in a front-strike machine in which a flat face platen 1 is carried by a carriage (not shown), the carriage moving over the top plate of the machine and receiving a letter space movement at each "printing" operation. The segmentally arranged type bars, each designated as a whole by the

reference numeral 2, are mounted to swing upwardly and rearwardly to impact at the printing point against the front face of the platen. Each type bar is pivoted to a hanger 3 secured to a type bar segment 4. Each type bar, as shown in Fig. 2, is formed with a transverse opening 5 shaped to receive a conical stem 6 of the associated type block, designated as a whole by the reference numeral 7. A drive fit is thus provided between each type bar and its block. Each block, shown in the present instance, comprises a cup-like portion or socket 8 which receives the needles 9 which form the type at their outer pointed ends. The needles of each type may be secured in place in their socket 8 by soft metal as indicated at 10.

In order to prevent the needle point type faces from being injured when one bar collides with another at or near the printing point, as indicated in Fig. 1, I provide each type bar with a contact member, cushion, pad or buffer 11 on the rear side thereof. This cushion may be made of any suitable material which is softer than the metal from which the type bar or the "printing" faces of the type are formed. In practice, I have found piano felt an excellent material from which to form the pads or cushions. Each cushion is cylindrical in form and preferably has its axis extending transversely of the bar and is located in the rear or back of the printing face of the type.

In order to secure each pad to its bar I prefer to form each type bar with a cylindrical socket 12 in the rear side or face thereof and back of the type block. This socket is formed by a flange which is annular in form and extends transversely of and rearwardly from the type bar and has its open mouth at the rear of the bar to receive the associated cylindrical pad 11. One end of this latter is seated in the socket against the bottom wall 13 thereof and the other end of the pad projects outwardly or downwardly beyond the rear side of the type bar and beyond the wall of the socket. The pads may be secured in place in their sockets and against accidental detachment therefrom by any suitable means, although I prefer to secure each pad in place by a threaded connection. As shown this threaded connection is established by forming the inner side

wall of each socket with a screw thread 14. The pads may be screwed into place in their sockets, thus effectively connecting each pad to its bar.

5 In Fig. 3 I have shown a modified form of construction in which the type bar proper 2^a is of standard construction. In this case a sleeve 15, separate and distinct from the bar, is slotted in one side, as at 16, to receive the body portion of the bar. The sleeve is adapted to surround the apertured head of the bar as shown, the body portion of the bar being seated in the slot 16. A thread 17 is tapped in the inner wall of the sleeve at the lower end portion thereof, as the parts appear in Fig. 3 and each sleeve 15 is brazed to its type bar. Otherwise the parts are constructed as previously described and the same reference numerals will be employed to designate the parts which correspond to those previously referred to.

Normally the projecting ends of the pads bear against a segmental type bar support 18, so that the pads in addition to preventing injury to the type faces act to cushion the type bars in their return movements.

Any suitable means may be employed for actuating the type bars. In the present instance I have shown type actions such as those ordinarily employed in the Nos. 10 and 11 Remington machines in which key levers 19 are fulcrumed on a fulcrum bar 20 and are provided with the usual finger keys 21. Each key lever is connected by a link 22 to a sub-lever 23, the hangers 24 of which are supported on a member 25 connected or formed integral with the type bar support 18. Links 26 are interposed between the sub-levers 23 and the type bars and returning springs 27 are each connected at one end to a key lever and at its opposite end to a hook 28. A universal bar 29 extends beneath the key levers and is connected by links 30 to crank arms 31 which project from the rock shaft 32. A centrally disposed crank arm 33 also projects from this rock shaft and is connected at its rear end to an upwardly extending link 34. The link 34 in turn is connected in the usual manner to the dog rocker (not shown) of the escapement mechanism by which the step-by-step feed of the carriage is controlled.

The construction is such that if one type bar should collide with another at or near the printing point, and before the first bar to be actuated has an opportunity to return to the normal position as shown in Fig. 1, the needle pointed type face on the second actuated bar will be brought into contact with the pad on the first bar, thus preventing injury to the type face on that bar which collides with the one at the printing point. The felt which constitutes the pads enables the needle faced type to strike the pads without injury to the type faces.

It will be understood that the pads constructed and arranged in the manner described are likewise effective to prevent an injury to the printing faces of the type whatever may be the character of the type employed.

It will be seen that by my invention I have provided simple and efficient means to prevent injury to the printing faces of types in a typewriting machine; and that in the form of construction shown in Fig. 3 the means in question may be applied to type bars of standard construction now in use.

Various changes may be made without departing from the spirit and scope of my invention.

What I claim as new and desire to secure by Letters Patent, is:—

1. A metallic type bar carrying a metallic type and having a socket in which is seated a buffer of material softer than the type and against which a part of another type bar is adapted to strike.

2. A type bar having a socket in the rear of the impact face of the type, and a pad seated in said socket.

3. A type bar having an interiorly threaded socket on the rear side thereof, and a pad threaded into said socket.

4. A type bar, a pad thereon, and a threaded connection between said type bar and pad.

5. A type bar having a threaded member on the rear of the type bar and back of the impact face of the type and a pad having a threaded connection with said member.

6. A type bar having a rearwardly opening socket, and a pad seated and secured in said socket and extending rearwardly from the type bar.

7. A type bar having a needle faced type and a socket in the rear of the type, and a pad seated and secured in said socket and extending rearwardly from the type bar.

8. A series of type bars mounted to strike at a common printing point, each of said type bars having a pad in the rear of the impact face of the type and attached at the end of the pad nearest the bar and extending rearwardly from the bar and from its point of attachment.

9. A type bar having a cylindrical socket, the axis of which extends transversely of the bar, and a cylindrical pad seated in said socket and extending beyond the walls thereof to form a buffer.

10. A type bar having an interiorly threaded cylindrical socket arranged in the rear or back of the type block, and a cylindrical pad threaded into said cylindrical socket.

11. A type bar having a flange formed integral therewith which flange forms a socket on the rear of the type bar, and a contact member seated in said socket, said

member being made of a material softer than that from which the type bar is formed.

12. A type bar, having an interiorly threaded socket formed in the body portion 5 of the type bar, said socket having an open mouth in the rear of the bar, and a contact member of material softer than the type bar threaded into said socket.

Signed at Ilion, in the county of Herkimer and State of New York, this 18th day of June, A. D. 1913.
